UNITED STATES PATENT OFFICE.

CHARLES FOSTER, OF PHILADELPHIA, PENNSYLVANIA.

SCAFFOLD.

Specification of Letters Patent No. 14,156, dated January 29, 1856.

To all whom it may concern:

Be it known that I, CHARLES FOSTER, of the city of Philadelphia and State of Pennsylvania, have invented a new and Improved 5 5 Scaffolding for Supporting the Workmen while Painting or Repairing the Fronts or Walls of Houses; and I do hereby declare that the following is a full, clear, and exact description of the same, reference being had to the 10 accompanying drawings, making a part of this specification, in which—

Figure 1, is a perspective view, showing the scaffold applied for the purpose, in front of a house; Fig. 2, a plan view of the 15 upper connections, and Fig. 3, a side view of the same; Fig. 4 a plan view of the lower connections, and Fig. 5, a side view of the same; and Fig. 6, a side view of one of the brackets, showing the manner of attaching 20 it to the posts or uprights—like letters indicating the same parts when on the different figures.

The nature of my invention consists in supporting the foot boards upon which the 25 workmen stand, by means of brackets constructed and applied in a peculiar manner to adjustable uprights; in the mode of constructing and operating the uprights; and also in the means of securing them in a firm 30 and perfectly safe position in front of the house or building, without fixing any part of the scaffold in direct contact with the wall of the building, thus allowing the workmen safe, convenient and unobstructed access to 35 every part of the surface which may be required to be painted or repaired.

Referring to the drawings, A—A—A, are the adjustable uprights; B—B, the brackets; C—C the foot boards resting on the brackets 40 (shown also by the dotted lines in Figs. 2 and 4).

D—D, are adjustable sliding ties for securing the uprights firmly at any requisite distance apart; E—E, are adjustable sliding jacks, having jointed and hooked adjustable arms, for securing the scaffold to the sills of the upper window frames; and F—F, are adjustable sliding hooks for securing the scaffold, also to the hinge eyes,

on the window frames of the second story 50 of the building.

The adjustable uprights (A) each consist of two or more square pieces of timber, about 4×4 inches thick, applied together and secured by collar bands (a—a), and 55 nut bolts (b—b) passing through the matched holes (c—c) in the same, so that the said bolts may be readily withdrawn by hand, and the uprights adjusted to any suitable length, by sliding the one upon the 60 other and then securing them firmly together by means of the said bolts and nuts, as shown in the drawings. The brackets (B) are applied on the inner side of the uprights (A), at about six feet apart, as 65 shown distinctly in Fig. 1, and are constructed of iron and in a branched form, so that when applied, the one branch forms a brace to the other in the usual manner. Their particular mode of construction and 70 application to the uprights is more distinctly shown in Fig. 6. The part d, forms the immediate support for the foot board, its one end being made to pass horizontally through a suitable hole in the upright, and 75 has a hole made vertically through it for the ready admission of a key bolt (e), and its other end (f) bent up so as to keep the foot board from sliding off toward the wall. The brace branch (g) is welded to the horizontal one, and also bent upward at its free end, as shown by the dotted lines h, so as to enter readily into a hole made in the upright, it having also a flange (i) fixed 80 around it so as to afford to the brace a broad 85 flat bearing against the upright, as shown in the drawing. The adjustable sliding ties (D, D,) each consists of two flat bars of iron held together by collar bands (j—j) so as to be free to slide, the one upon the other, 90 in a well known manner. One of these bars has a series of holes made through it about an inch apart, and the collar band (fixed on the end of the other) has also a matching hole in it, through which and the bar a 95 key bolt (k) is inserted so as to fix the adjusted length of the tie. The ties just described are secured to the uprights (A, A,

A,) by means of nutted bolts (7—7) which pass horizontally through them, as shown in the drawings.

The adjustable sliding jacks (E—E) each 5 consists of two pieces of iron, made and fitted together so as to slide, the one upon the other, being held together by collar bands (m, m.—see Fig. 3) and adjusted by a key bolt and holes, like the ties D, their outer 10 ends (n and n') projecting downward at right angles, and being made so that the outside one (n) may bear against the outside of the window sill (G), and the inside one so as to receive a screw bolt (o) whose 15 inner end can be brought up against the inner side of the sill—a small metallic plate or block, intervening so as to prevent the sill being indented or injured by the end of the said bolt in screwing it up against the 20 same, when the jack is thus being fixed to the sill. A broad flat projection (p) is also made on the outer slide, and to this is attached, by a pivot, an adjustable hooked tie or brace (q) (consisting of a hooked rod 25 capable of sliding within a tube, and being secured therein by a screw bolt (r) in a well known manner), which tie or brace is also flattened at its inner end, and capable of being moved (right and left) upon the 30 projection (p), the connecting pivot being riveted to the same. This tie or brace (q) is also adapted (by means of a set screw (s) which passes through a slot in the tie at this part) so as to be fixed at any angle which 35 may be required in connecting the hooked end of the same with an adjustable eye-plate on the upright. This eye-plate (H) (see Fig. 2) is constructed so as to be adjusted at any point on the upright to suit 40 the height of the jacks on the window sills, and is secured to the uprights by means of a binding bolt and nut (t), and has also an eye or loop fixed on the inner side, into which the hook of the tie (q) is inserted in 45 connecting the uprights (A) to the window sills (G) of the building. I sometimes also make use of a rigid tie brace, (u) having a hook at one end and a notch at the other, as shown in the drawing (Fig. 3) for connecting 50 the sliding bars (D) with the lower part of the jack, in a direct manner as shown in Fig. 2. The adjustable sliding hooks (F—F) are each made to slide and be fixed together in the same manner as the 55 sliding ties (D—D); and have a hook (v) formed at each end (see Figs. 4 and 5)—the one hook being adapted for connecting with an eye-plate (H') constructed and applied to the upright as before described, and the 60 other hook adapted for entering the eye of the hinge, on the window frame—the shutter being removed therefrom.

In combining these several parts together and producing a scaffold for the purposes

mentioned, I first adjust the lengths of the 65 uprights to suit the height of the building, and insert the brackets so as to arrange for the foot boards at about 6 feet apart; I then place a board or plank (W) (Fig. 1) upon the pavement, parallel with, and three 70 or four feet from the front of the building, and upon this erect the uprights and connect them respectively with the lower eyes of the hinges on the window frames of the second story, by means of the hooked ties 75 or braces (F, F,) as shown in Figs. 1 and 4. I then adjust and apply the jacks (E—E) one at each end of the sills of the upper window frames, and connect the uprights therewith by means of the tie braces (g)— 80 the eye-plates (H, and H'), being adjusted and fixed at the proper height on the uprights, to suit the position of the jacks in the one case, and the hinge eyes in the other. The two ties of each window, being 85 thus arranged and connected with the three uprights respectively, they are each in a horizontal oblique position in relation to the uprights and the front of the building (as shown in the drawings) and hence operate, both as braces and ties, and prevent any swaying movement of the uprights. The foot-boards (C—C) are now placed upon the brackets, as shown in Fig. 1, and 90 thus afford convenient footing for the workmen in putting up and attaching the long ties (D and D), which are now fixed to the uprights in horizontal positions, the one about 8 feet from the pavement, and the other a few feet below the upper ends of 95 the uprights, as shown in Fig. 1. The scaffold is now firm, secure and ready for use. The uprights being placed, in putting up the same, at a sufficient distance from the 100 wall to allow about six inches space between the latter and the projecting ends of the brackets, and the scaffold being held in position (as shown in Fig. 1) in front of the building, without direct contact with any part of the wall, the workmen, standing 105 upon the foot boards, have convenient and unobstructed access to every part of the same—which is of great importance, especially in “penciling” the fronts of houses; while the whole apparatus is very simple 110 and inexpensive, easily and quickly put up or taken down without any extraneous support, or even the necessity of driving a nail, using a hammer, or removing a brick out of the foot pavement upon which it is usually erected.

I do not claim separately, either of the several devices constituting the scaffold herein described; but

What I claim as my invention and desire 125 to secure by Letters Patent is—

A scaffold consisting of the combination of the adjustable uprights (A, A, A) the

movable brackets (B—B) for supporting the foot boards; and the horizontal, adjustable ties (D—D); the same being arranged, combined together and operating as described, and also held or secured in a perfectly steady position, near the building which is to be repaired or painted, without direct contact with the wall of the same, by means of the jacks (E—E) and the braces (F—F) constructed, applied and operating substantially as set forth and described.

CHARLES FOSTER.
